BY

R. A. Bourne

ATTORNEY

UNITED STATES PATENT OFFICE.

HENRY J. GAISMAN, OF NEW YORK, N. Y., ASSIGNOR TO AUTOSTROP PATENTS CORPORATION, OF DOVER, DELAWARE, A CORPORATION OF DELAWARE.

BLADE HOLDER.

Original application filed June 24, 1924, Serial No. 721,972. Divided and this application filed December 17, 1926. Serial No. 155,400.

My invention relates to improvements in blade holders and is particularly applicable for detachably retaining blades in safety razors and blade stropping mechanism.

5 The object of my invention is to provide a blade holder in which a razor blade may be readily applied and may be rocked for stropping its edge.

My invention comprises two plates or 10 members adapted to receive a blade therebetween, one of which plates is secured to a shaft and the other plate is rotatable with respect to the shaft, said shaft being provided with a gear, and another shaft having 15 a gear in mesh with the first named gear, whereby when the blade holder is reciprocated along a strop with the second named shaft in engagement therewith the blade holder will be rotated or rocked for stropping the edge of the blade.

20 My invention also comprises novel details of improvement that will be more fully hereinafter set forth and then pointed out in the claim.

25 Reference is to be had to the accompanying drawings forming a part hereof, wherein:

Fig. 1 is a side view of a safety razor embodying my invention;

30 Fig. 2 is a face view illustrating parts in position for use;

Fig. 3 is a face view illustrating the members of the holder spread apart and a blade upon one of said members;

35 Fig. 4 is a cross section on the plane of line 4, 4, in Fig. 2;

Fig. 5 is an edge view, partly in section, on line 5, 5, in Fig. 2;

40 Fig. 6 is a section on line 6, 6, in Fig. 3, and

Fig. 7 is a section on line 7, 7, in Fig. 2.

Similar numerals of reference indicate corresponding parts in the several views.

The blade holder comprises plates or mem-

45 bers 1, 2 hinged or pivoted together in such a manner as to embrace the blade 3 and bear against opposite sides thereof. One of said plates or members, as 1, is secured to a shaft 4, and is shown provided with spaced webs

50 or ears 5 coiled around the shaft and may be secured thereto in any suitable way, as by denting the webs into the shaft at 6, or by riveting the parts together. The plate or member 2 is pivotally mounted upon shaft

4 as by means of webs or ears 7 coiled around the shaft so that said plate may rotate with respect to the shaft and to the plate 1. The plate 1 is provided with means for positioning the blade upon the plate and for clamping the plates or members together upon the 55 blade, arranged as follows:—An arm or latch 8 is pivotally supported upon plate 1, as by means of rivet 9, so as to swing edgewise respecting said plate, the plate being shown offset at 1^a to accommodate the arm or latch 8 so that the blade 3, when resting upon the plate 1, may have a portion overlying the arm or latch so as not to interfere with the latter, as shown in Fig. 6. The arm or latch 60 8 is provided with jaws or a recessed portion 8^a, near its free end, adapted to receive the edges of plates or members 1, 2 therebetween to retain said plates clamped upon the blade, as indicated in Figs. 4 and 7. Jaws 8^a are offset from the plane of the arm 65 or latch 8 at the pivot 9 so as to receive the corresponding edges of the two plates 1, 2 and the blade 3 therebetween, as indicated in Figs. 5 and 7. An arm or latch 8 is shown at 70 opposite ends of plates 1, 2, near the inner portions of the latter, to correspondingly clamp and retain the end portions of said plates.

The blade 3 is shown provided with notches or recesses 3^a at its ends near the 75 corners adjacent to the heel of the blade opposite its cutting edge, providing projections 3^b at the inner corners of the blade which are adapted to be opposed by lugs or projections 10 located upon the inner portions of 80 the arms or latches 8 to oppose the blade projections 3^b. The arms or latches 8 are shown provided with stops 11 adapted to engage the adjacent edge of plate 1 to limit the rotation of said arms relatively to said 85 plate, whereby when the arms have been swung from the position shown in Fig. 2 to the position shown in Fig. 3 the projections 10 will be located in position to receive a corresponding recess 3^a of the blade with the 90 adjacent projection 3^b thereof opposed to the corresponding projection 10.

When a blade is to be inserted in the holder the arms or latches 8 are moved to the 95 position shown in Fig. 3, to release the plates or members 1, 2; the plate 2 is swung away from plate 1, and a blade may be laid upon the latter plate in the position shown in Fig.

3, so that the projections 10 will enter the recesses 3^a and the projections 3^b of the blade will be behind the projections 10. When the blade is to be retained the plate 2 is swung 5 upon the blade and the arms or latches 8 are moved inwardly so that the jaws 8^a will embrace or grip the plates 1, 2 therebetween, whereupon the projections 10 are moved out of the recesses 3^a and away from cooperation 10 with the projections 3^b of the blade, as indicated in Fig. 2. In such position of the parts the blade would be loose between the plates 1, 2, which is the operative position 15 of the latter, and in order to retain the blade between said plates when clamped against the blade I provide the blade with apertures, indicated at 12, to receive corresponding projections 13 extending inwardly from plate 1. The projections 13 may be formed by 20 bossing or pressing the metal of plate 1, as indicated in Fig. 4. The apertures 12 of the blade are shown related in such a manner to one another as to produce a designation, such as a word or symbol. The arrangement 25 of the apertures 12 is such with respect to projections 13 of plate 1 that when the blade is laid upon said plate certain of the apertures 12 of different letters will be in position to receive certain projections 13, where- 30 by when the plates 1, 2 are clamped upon the blade by means of the jaws 8^a the blade will be prevented from sliding from the holder and will be retained in the desired position.

35 My improved blade holder is adapted for use in a safety razor, or in connection with blade stropping means adapted to rock the blade back and forth for stropping purposes whether such stropping means be incorpo- 40 rated in a safety razor or only in a stropping machine. In the example illustrated in Fig. 1 I have shown my improved holder in a

safety razor provided with means for stropping the blade, such as the well known Auto Strop safety razor. The razor frame 15 is provided with spaced uprights 15^a in 45 which the shaft 4 is journaled to rock, a gear 16 on said shaft being in mesh with a gear 17 secured to a shaft or roller 18 journaled between the uprights 15^a, in a well known way. A strop is adapted to pass between the 50 shaft or roller 18 and base 19 of the frame so that when the frame is reciprocated along the strop the blade holder will be rocked back and forth by reason of the engagement of the strop with the shaft or roller 18. 55 Frame 15 is shown provided with a guard 20 that is pivotally supported at 21, (on opposite sides), to base 19, a projection 22 on the guard being in position to be manually operated to cause the stops 23 on the guard 60 to engage the blade edge to retain the latter in shaving position and to release the blade for stropping purposes and for replacement of a blade in the blade holder.

Although I have shown two projections 13 65 on plate 1 to engage corresponding apertures 12 in the blade it will be understood that one or more of such projections may be provided on said plate suitably located to engage the corresponding aperture or apertures in the 70 blade.

This application is a division of my application filed June 24, 1924, Serial No. 721,972.

Having now described my invention what 75 I claim is:

A safety razor including two shafts geared together, and two blade-holding plates mounted on one of said shafts, one of said plates being rotatable with respect to said 80 shaft.

HENRY J. GAISMAN.
